UNITED STATES PATENT OFFICE

ARCHDALE J. JONES, OF NEW YORK, N. Y., ASSIGNOR TO BRADFORD DARRACH, ALAN D. MARKS, AND FRANKLIN J. FOSTER

DESIGN FOR A CASING OR SIMILAR CONTAINER

Application filed December 12, 1929. Serial No. 33,760. Term of patent 7 years.

To all whom it may concern:

Be it known that I, ARCHDALE J. JONES, a subject of the King of Great Britain, and residing at New York, borough of Manhattan, county of New York, and State of New York, have invented a new, original, and ornamental Design for Casing or Similar Container, of which the following is a specification, reference being had to the accompanying drawings, forming part hereof, and in which—

Fig. 1 is a top plan view of a casing or similar container showing my new design.

Fig. 2 is a side elevational view thereof.

Fig. 3 is an end view thereof.

Fig. 4 is an opposite end view thereof.

I claim:

The design for a casing, or similar container substantially as shown.

ARCHDALE J. JONES.
